US00D857267S

(12) **United States Design Patent** (10) Patent No.: **US D857,267 S**
(45) Date of Patent: **** Aug. 20, 2019**

(54) **COMPACT EXTERNAL LIGHT**

(71) Applicant: **Lume Cube, Inc.**, San Diego, CA (US)

(72) Inventors: **Mornee Patrick Sherry**, San Diego, CA (US); **Matthew Milton Cummins**, San Diego, CA (US)

(**) Term: **15 Years**

(21) Appl. No.: **29/637,047**

(22) Filed: **Feb. 13, 2018**

Related U.S. Application Data

(62) Division of application No. 29/539,848, filed on Sep. 17, 2015, now Pat. No. Des. 831,868.

(57) **CLAIM**

We claim the ornamental design for a compact external light, as shown and described.

DESCRIPTION

FIG. 1 is an upper right front perspective view of a compact external light;

FIG. 2 is a second perspective view of a compact external light;

FIG. 3 is a front elevational view of a compact external light;

FIG. 4 is a right side elevational view of a compact external light, the left side elevational view is a mirror image thereof;

FIG. 5 is a rear elevational view of a compact external light;

FIG. 6 is a top plan view of a compact external light; and,

FIG. 7 is a bottom plan view of a compact external light, dashed elements are unclaimed.

1 Claim, 5 Drawing Sheets
